INVENTOR:
Nicholas La Jone,
PER:
Dyrenforth, Lee, Clinton & Co.,
ATTORNEY:

UNITED STATES PATENT OFFICE.

NICHOLAS LA JONE, OF CHICAGO, ILLINOIS, ASSIGNOR TO INLAND RUBBER COMPANY, OF CHICAGO, ILLINOIS, A CORPORATION OF ILLINOIS.

DESIGN FOR AN AUTOMOBILE TIRE.

Application filed February 8, 1928. Serial No. 25,276. Term of patent 14 years.

To all whom it may concern:

Be it known that I, NICHOLAS LA JONE, a citizen of the United States, residing at Chicago, county of Cook, and State of Illinois, have invented a new, original, and ornamental Design for an Automobile Tire, of which the following is a specification, reference being had to the accompanying drawing, forming a part hereof, in which—

Fig. 1 is a plan view of the tire; and
Fig. 2 is a view of the tire in cross section.

I claim:

The ornamental design for an automobile tire as shown.

NICHOLAS LA JONE.
